United States Patent Office.

EDWARD HAMLIN, OF DELANCO, NEW JERSEY.

Letters Patent No. 85,090, dated December 22, 1868.

IMPROVEMENT IN SWAGE FOR SAW-TEETH.

The Schedule referred to in these Letters Patent and making part of the same.

To all whom it may concern :

Be it known that I, EDWARD HAMLIN, of Delanco, Burlington county, State of New Jersey, have invented a Swage for the Teeth of Saws; and I do hereby declare the following to be a full, clear, and exact description of the same.

My invention consists of an instrument composed of parts arranged and adapted to each other, in the peculiar manner fully described hereafter, so as to form a swage, which, while it serves to upset the cutting-points of saw-teeth, will, at the same time, determine their proper width and shape.

In order to enable others skilled in the art to make and use my invention, I will now proceed to describe its construction and operation, reference being had to the accompanying drawing, which forms a part of this specification, and in which—

Figure 1 is a longitudinal section of my improved swage for saw-teeth;

Figure 2, an end view, looking in the direction of the arrow, fig. 1;

Figure 3, an exterior view of the instrument; and

Figure 4, a view with the stem detached from other parts of the instrument.

A is a steel stem, appropriately formed at one end, *a*, for receiving the blow of a hammer, and having at the opposite end a projection, *b*, at the junction of which with the main body of the stem are two abrupt shoulders, *c c*, on the latter.

The edges *d d* of the stem A are slightly inclined, and are so adapted to the slot of a sleeve, B, that the stem will penetrate the same to a short distance back of the shoulders *c c*, where the stem can be wedged tight to the sleeve, the stem fitting snugly into the same in a lateral direction.

Two pieces of steel, D and D', with swaged ends *z*, are fitted snugly to the interior of the sleeve B, the outer edges of the said pieces D and D' being adapted to the bevelled end of the slot in the sleeve, while their inner edges are adapted to the parallel portions *x x* of the edges of the projection *b*, so that, on driving the stem into the sleeve, the shoulders *c c* will bear against the ends of the pieces D and D', and the whole of the parts will become so tightly wedged together as to be equivalent to a solid swage.

On referring to fig. 2, it will be seen that the sides of the slot in the sleeve are notched at the points *y*, so that there are, in the end of the instrument, two angular recesses, with inclined sides.

The instrument having been so adjusted to the tooth of a saw that the point of the latter penetrates one of the recesses, the end, *a*, of the stem is struck repeated blows with a hammer, until the end of the tooth is so far upset as to fill the recess, which thus determines the shape and width of the cutting-point.

But one piece, D, may be used, as shown in fig. 5, in which case there will be but one recess. I prefer two, however, as described above.

I claim as my invention, and desire to secure by Letters Patent—

A sleeve, having recesses *y y*, and fitted to a stem, and to a detachable die, substantially as and for the purpose described.

In testimony whereof, I have signed my name to this specification, in the presence of two subscribing witnesses.

EDWARD HAMLIN.
